LAMP FIXTURE

August O. Elting, Chicago, Ill.

Application August 28, 1941, Serial No. 408,624

4 Claims. (Cl. 248—342)

The invention relates to improvements in lamp fixtures of a type having wire-receiving channelled arms and more particularly to novel means for housing and concealing the wires in said channel.

The structure of the invention is particularly adapted to be embodied in lamp fixtures of the type having a plurality of radially extending fixture arms, each of which includes an intermediate body portion in the form of an inverted channel along which the usual electrical wires extend. Although the channels in said arms are of sufficient depth to normally conceal the wires from view, instances of installation or use may require the provision of suitable means to completely house and conceal the wires irrespective of the angle of observation of the fixture. For example, should the wires not be drawn taut along the channel they tend to sag and are thus exposed to view.

It is, therefore, an object of the invention to provide a channelled fixture arm with novel readily mounted means to conceal electrical wires contained therein.

Another object is to provide a novel inexpensively manufactured cover strip adapted for ready installation in or removal from a wire containing channel.

Another object is to provide a channelled fixture arm of the type having a flexible cover strip mounted at its ends in said channel with means to support the intermediate portion of said strip.

The foregoing and such other objects of the invention as will appear hereinafter as the description proceeds, will be more readily understood from a perusal of the following specification; in which reference is had to the accompanying drawing, wherein:

Fig. 1 is a fragmentary longitudinal sectional view of a lamp fixture body showing a channelled arm thereon embodying the invention.

Fig. 2 is an end elevational view of the arm mounting taken substantially on line 2—2 of Fig. 1 and partially broken away.

Fig. 3 is a perspective view of the resiliently flexible cover strip.

Fig. 4 is a sectional view taken on line 4—4 of Fig. 1.

Fig. 5 is a sectional view similar to Fig. 1 showing a modified form of the invention.

Fig. 6 is a longitudinal sectional view, similar to Fig. 1, showing another type of fixture arm embodying the invention illustrated in Fig. 1.

Fig. 7 is a sectional view taken substantially on line 7—7 of Fig. 6.

Fig. 8 is a view similar to Fig. 6 illustrating the embodiment of Fig. 5 in the modified type of arm.

In the embodiment illustrated in Figs. 1 and 2, the invention is contained within a channel shaped arm 11 mounted at one end in the cir-

cumferential wall 12 of a conventional fixture body 13. The precise shape the arm is to take is determined by the specific design of the lamp as a whole but in each instance the arm 11 includes an intermediate body portion 14 in the form of an inverted wire-receiving channel terminating at one end in a tubular portion or nipple 15 which communicates with the channel, and at the other end in a substantially vertically disposed tubular portion 16. The upper end of the tubular portion 16 is suitably formed to support a candle cup 17 and is externally threaded to receive a conventional lamp socket 18.

Electric wires 19 connect with and extend from the socket 18 downwardly through the tubular portion 16 and then along the channel in the body portion 14 and emerge from the arm through the nipple 15 within the interior of the fixture body 13 where they are connected to a source of electric current. When properly wired, that is, when the wires 19 are drawn and held taut within the channel 14 so as to dispose them in substantial contact with the closed upper side of the channel, said wires normally are concealed from view. However, it sometimes happens that said wires are left or become slack and consequently are partially exposed below the bottom edges of the channel side walls. Before entering into a detailed discussion of the precise structure and arrangement directed to overcome this possibility of wire exposure, a brief description of a preferred construction and method of mounting the arms to the fixture body is desirable.

As shown, a circumferential external flange 21 is formed inwardly of the free end of the nipple 15 to provide an abutment against the outside face of the fixture body wall 12 when the arm is mounted in place. One or more substantially square radial lugs 22, best shown in Fig. 2, preferably are formed integral with the nipple and flange 21. These lugs are arranged to pass through similar spaced recesses or notches 23 in the edge of the fixture body wall opening. To assemble, the nipple 15 is inserted into the body wall opening and its free end is expanded and preferably rolled outwardly radially and downwardly tightly against the inside face of the wall 12. Expansion and rolling of the nipple draws the flange 21 tightly against the outside face of the fixture body and carries the lugs 22 outwardly radially so as to substantially fill the recesses 23. Obviously, arms mounted in this manner are securely held against twisting or turning within their mounting.

The cover strip 24 embodying the features of the present invention is best illustrated in Fig. 3 and consists of an elongated strip of resiliently flexible material formed to conform substantially to at least a part of the contour of the fixture arm within which it is to be mounted. As

shown, the strip 24 is substantially the same width as the inside width of the channel so as to be embraced snugly thereby when in place. One end of the strip 24 is offset upwardly at 25 and then outwardly to define a tongue 26 which is less in width than the body portion of the strip and is adapted to be inserted freely within the nipple 15. The offset 25 abuts the end of the nipple to limit insertion of the tongue.

While mounting the cover strip, its slightly tapered free end portion 27 initially assumes a position substantially as illustrated in dotted lines in Fig. 1. To complete the mounting, the strip is flexed sufficiently to permit its free end to be inserted into the tubular portion 16 and it then is urged upwardly into the position shown in full lines. The inherent resiliency of the strip maintains the end portion 27 in frictional engagement with the opposing surface of the tubular portion 16 and consequently prevents displacement of the strip.

The embodiment of the invention illustrated in Fig. 5 is substantially like that just described except that in this instance the cover strip 24a is longer and its free end portion 27 has an outwardly turned lip 28 arranged to hook over the upper end of the tubular arm portion 16. To mount this strip, the tongue 26 is engaged in the nipple 15 and its free end portion is forced into the tubular portion 16 into its final position. This construction provides positive means for detachably locking both ends of the strip in place irrespective of the degree of friction resulting from the resiliency of the strip. It should be apparent, therefore, that the cover strip 24a may be made from material having less resiliency than the frictionally held strip 24.

In Fig. 6, the invention is shown applied to another type of fixture arm wherein the intermediate body portion 14a is of considerable length. The specific arm illustrated is particularly adapted to support fluorescent tube sockets and has a substantially rectangular socket containing receptacle 29 at the upper end of its tubular portion 16. In the particular embodiment illustrated, the receptacle 29 is made of two parts, one of which consists of a base plate 31 detachably secured to the upper end of the tubular portion 16 by an arrangement constructed in the same manner as the mounted end of the arm illustrated in Fig. 1. In other words, the nipple and lug structure of Fig. 1 is provided on both ends of the arm in Fig. 6.

The cover strip 24b preferably is like that illustrated in Fig. 3 except that it necessarily is longer. Obviously because of its length and inherent resiliency, a strip of such length normally would tend to bow or bulge downwardly below the bottom edges of the channel side walls. This may be avoided by bridging the channel at one or more places with suitable supports, such as for example, drive screws 32. As shown, the screws 32 extend transversely through the channel side walls beneath the cover strip 24b. In the event two such bridges are provided, one drive screw is mounted prior to insertion of the cover strip and the second one is mounted only after the free end portion 27b of said strip is inserted into the tubular portion 16.

The embodiment illustrated in Fig. 8 discloses

an arm substantially like that shown in Fig. 6 except that in this instance the bottom wall 31a of the socket receptacle 29 is formed integral with the upper end of the tubular portion 16 and consequently affords a substantially flat face at said upper end. The cover strip 24c illustrated is like the cover strip disclosed in the embodiment in Fig. 5 except that it, like the strip shown in Fig. 6, is longer. The flat upper end face of the tubular portion 16 affords means for co-active engagement by a lip 28 on the end of the cover strip, consequently this strip also may be made of material having less resiliency than the one shown in Fig. 6.

15 Although exemplary forms of the invention have been illustrated and described in detail it should be understood that the disclosures are not restrictive but that the invention may embody variations in detail structure and that the cover strip may be used in association with channelled fixture arms embodying other details and shapes without departing from the spirit of the invention or the scope of the appended claims.

I claim:

25 1. In a lamp fixture, a fixture arm including a body portion providing an inverted wire-receiving channel and having a tubular portion at each end communicating with the channel, and a resiliently flexible cover strip having a tongue at one end engageable in one of said tubular portions and having its other end engageable in the other tubular portion by flexing said cover strip to retain the cover strip in the channel to house wires therein.

35 2. In a lamp fixture, a fixture arm including a body portion providing an inverted wire-receiving channel and having a tubular portion at each end communicating with said channel, a resiliently flexible cover strip having one end insertable in one of said tubular portions and having its other end formed to co-act with the other tubular portion upon flexing said cover strip to retain the cover strip in the channel to house wires therein, and a shoulder adjacent one 40 end of said strip to limit the insertion of said strip in the tubular portion.

3. In a lamp fixture, a fixture body, a fixture arm including a body portion providing an inverted wire-receiving channel terminating adjacent one end in a tubular portion, a nipple at each end of said arm communicating with said channel, one of said nipples co-acting with the fixture body to mount the arm in place, a lamp socket receptacle engaged with the other nipple, 45 and a resiliently flexible cover strip in said channel having one end engageable in the nipple at the mounted arm end and having its other end co-acting with the tubular portion upon flexing said cover strip to retain the cover strip within the channel.

4. An article of the character described comprising a fixture arm including a body portion providing an inverted wire-receiving channel and having a tubular portion at each end communicating with said channel, a resiliently flexible cover strip arranged in said channel and having its end portions engaged in said openings, and means in the body portion of said arm to support the intermediate portion of said cover strip.
